UNITED STATES PATENT OFFICE.

ROBERT H. BEAUMONT, OF RADNOR, PENNSYLVANIA, ASSIGNOR TO R. H. BEAUMONT COMPANY, OF PHILADELPHIA, PENNSYLVANIA, A CORPORATION OF PENNSYLVANIA.

SKIP HOIST.

Application filed March 10, 1928. Serial No. 260,626.

Objects of the present invention are to dispense with bent rails at the junction of mutually inclined straight rails or tracks; to provide for holding straight rails at the curved junction points to gauge and to the supporting wall or structure; to resist the reaction of the oblique stress due to the fact that the pull of the cable which is attached to the skip bucket is not parallel with the tracks, more particularly the curved tracks; to simplify and improve and avoid difficulties in skip hoist designs; and to standardize skip tracks by providing for the use of all straight rails of any required length and of standard junctions or frogs for each standard size skip bucket.

Other objects of the invention will appear from the following description, but generally stated, the invention may be said to comprise a supporting structure, straight parallel rails arranged in mutually inclined sections, and a yoke having means for securing it to the supporting structure and having confronting arms provided with concentric curved wheel guides and said yoke also provided with brackets adapted to support the end parts of the straight rails in alignment with the curved guides.

The invention also comprises the improvements to be presently described and finally claimed.

In the following description reference will be made to the accompanying drawings forming part hereof and in which Figure 1 is an elevational view, partly in section and somewhat diagrammatic, illustrating a skip hoist embodying features of the invention.

Fig. 2 is a view drawn to an enlarged scale and illustrating the construction at the junction of the end parts of the rails.

Fig. 3 is a transverse sectional view of the construction shown in Fig. 2, and

Fig. 4 is a sectional view taken on the line 4-4 of Fig. 2.

In the drawings 1, generally, represents a supporting structure. 2 and 3 are straight parallel rails arranged in mutually inclined sections of which three are shown in Fig. 1,

but the number is not important. 4 is a yoke having means 5, shown as perforated ears at the base of the yoke, for securing it to the supporting structure. The yoke 4 also has confronting arms 6 provided with concentric curved wheel guides 7 and 8. The yoke is also provided on opposite sides of the wheel guides with brackets 9 and 10 adapted to support the end parts of the straight rails in alignment with the curved guides 7 and 8. In dotted lines in Fig. 3 there is shown a bale guide wheel 11, which is also shown in Fig. 1, and in Fig. 1 there is shown a skip bucket 12, and in dotted lines 13 the cable by which it is operated. The cable in passing over the guide sheave 14 and acting upon the wheel 11 exerts a pull on the track oblique to the direction of the track. The described yoke resists this pull at the junctions, keeps the rails in gauge, and affords means for securing them to the supporting structure.

It will be obvious to those skilled in the art to which the invention relates that modifications may be made in details of construction and arrangement and matters of mere form without departing from the spirit of the invention which is not limited to such matters or otherwise than the prior art and the appended claims may require.

I claim:

1. In a skip hoist the combination of a supporting structure, straight parallel rails arranged in mutually inclined sections, and a yoke having means for securing it to the supporting structure and having confronting arms provided with concentric curved wheel guides and said yoke also provided with brackets adapted to support the end parts of the straight rails in alignment with the curved guides.

2. In a skip hoist the combination of straight parallel rails arranged in mutually inclined sections, and a yoke having confronting arms provided with concentric curved wheel guides and said yoke also provided with brackets adapted to support the end parts of the straight rails in alignment with the curved guides.

ROBERT H. BEAUMONT.
